UNITED STATES PATENT OFFICE.

WILLIAM T. MURRAY, OF BALDWIN, KANSAS.

CURTAIN FOR VEHICLE TOPS.

1,034,280.

Specification of Letters Patent. Patented July 30, 1912.

Application filed November 9, 1910. Serial No. 591,484.

To all whom it may concern:

Be it known that I, WILLIAM T. MURRAY, a citizen of the United States of America, residing at Baldwin, in the county of Douglas and State of Kansas, have invented new and useful Improvements in Curtains for Vehicle-Tops, of which the following is a specification.

This invention relates to curtains for vehicle tops, and it has particular reference to a curtain applied to the back of the vehicle top.

In vehicle tops, as ordinarily constructed, when the same are lowered, the back requires to be folded, thus preventing the presence of rigid guides for a curtain of a considerable length.

The object of the present invention is to produce an improved curtain guide for a spring actuated roller curtain, said guide being composed of a plurality of members suitably spaced apart so as not to interfere with the folding of the flexible back member of the top.

Further objects are to simplify and improve the construction and operation of the curtain and the coacting guides.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the invention, may be resorted to when desired.

In the drawings,—Figure 1 is a vertical sectional view of a buggy top, the back of which is provided with the improved spring-actuated roller curtain. Fig. 2 is a rear elevation of the back of the vehicle top, parts having been broken away in order to

expose subjacent parts. Fig. 3 is a horizontal sectional view taken on the line 3—3 in Fig. 2. Fig. 4 is a perspective detail view of one of the curtain guides detached. Fig. 5 is a perspective detail view of the top guides. Fig. 6 is a perspective detail view of the bottom guides.

55

Corresponding parts in the several figures are denoted by like characters of reference.

The vehicle top A is supported in the usual manner by means including the front bow B, the rear bow C and the middle bow D; jointed braces E being provided to support the top in extended position.

The back member 1 of the top is supported essentially by the rear bow C, said back member being constructed in the usual manner of flexible material, such as oil cloth, rubber cloth or the like. An opening or aperture 2 is formed midway between the sides of said back member, said opening extending nearly from the top to the bottom thereof. In cutting or forming said aperture, the material or part of the material is left attached at the side edges of said aperture to form flaps, the use of which will be presently made apparent.

The curtain 3 is made of flexible material similar to that of which the back is constructed, and said curtain is suitably attached to and adapted to be wound upon a spring actuated roller 4 supported for rotation in brackets 5 which may be mounted upon the top of the rear bow C. The curtain is provided adjacent to its side edges with hems 6 in which flexible cords 7 are confined.

Suitably secured upon the back 1 adjacent to the side edges of the aperture 2 are guide members G which may be suitably formed of wire by bending the same, as clearly indicated in Fig. 4, to form two U-shaped tongues 8, 8 connected together by a bridge piece 9 and provided with terminal divergent legs 10; said U-shaped tongues being bent toward each other so as to form a vertically disposed loop 11. A plurality of

these guide members are secured adjacent to each side edge of the aperture 2, the flaps 12 adjacent to said side members being inserted into the vertical loops 11, and afterward lapped over the body of the back member and secured thereto by stitching 13. The legs 10 of the guide members B are provided with terminal eyes 14, and not only are said guide members firmly secured by stitching upon the back member 1, but the portions of the flaps 12 which are inserted into the loops 11 are firmly stitched or otherwise attached to said loops, thus forming vertical guide grooves 15 for the reception of the reinforced side edges of the curtain. It is obvious that when the latter is lowered and the side edges thereof reinforced by the flexible cords within the hems 6 are guided in the grooves 15, the parts will be retained in assembled condition by the guide members, the latter being so constructed and proportioned that the reinforced side edges of the curtain may not be readily withdrawn from between the tongues 11.

Adjacent to the top and the bottom of the aperture 2 specially constructed guide members are used, said guide members being connected together by a cross bar 16. Each of the guides, here designated G', is provided only with a single leg, here designated 10', which in the case of the top guides are extended to and connected with the top of the rear bow C, while in the case of the bottom guides, the said legs may be connected with or attached to the back of the seat, as shown at 17, or with some other suitable point of attachment. The cross bars 16 also serve for engagement with the hook members 18 suitably attached adjacent to the lower edge of the curtain which may thus be retained when drawn down against the tension of the spring actuated roller for the purpose of obstructing the opening 2, or it may be retarded by engagement with the top cross bar when the curtain is raised. It would be within the scope of the invention to provide several of the guide members with connecting cross bars, as shown at 16, in order that the curtain may be secured in an intermediate position, an example of this being shown in dotted lines at 16' in Fig. 2 of the drawings.

The curtain may be provided with a window, as shown at 20, the same being constructed of celluloid or other material which is capable of being rolled without danger of breakage.

From the foregoing description, taken in connection with the drawings hereto annexed, the operation and advantages of this invention will be readily understood. The

construction is simple, inexpensive and thoroughly efficient for the purposes for which it is provided.

65

Having thus described the invention, what is claimed as new, is:

1. In a carriage top, a flexible back member, a curtain associated therewith, and curtain guides consisting of folds formed of portions of the back member, said folds presenting grooves having unbroken surfaces to receive and guide the side edges of the curtain; in combination with spaced guides, each including a pair of tongues bent to 75 form a vertically disposed loop for the reception of the folds constituting the guide grooves.

2. In a carriage top, a flexible back member having an aperture, spaced guides adjacent to the side edges of said aperture, each of said guides including a pair of tongues bent to form a vertically disposed loop, flaps adjacent to the side edges of the aperture inserted into and secured in said loops, 85 folded over the guide members and attached to the body of the back member to form vertical flexible guide grooves, a suitably supported spring actuated roller, and a curtain connected with said roller and having thickened reinforced side edges operating in the vertical flexible guide grooves.

3. In a vehicle top, a flexible back member having an aperture, flaps adjacent to the side edges of said aperture, said flaps being 95 folded to present vertical grooves, rigid guide members secured at intervals in the folds between the back member and the side flaps and including tongues combining to form vertical guide loops, a suitably supported spring actuated roller, and a flexible curtain upon said roller having reinforced side edges operating in the vertical guide grooves.

4. In a vehicle top, a flexible back member having an aperture, flaps adjacent to the side edges of said aperture, said flaps being folded to form vertical guide grooves, rigid guide members reinforcing said guide grooves at intervals, some of said guide 110 members being connected in pairs by bridge members extending across the aperture, a suitably supported spring actuated roller, and a flexible curtain connected with said roller and having reinforced side edges 115 engaging the guide grooves, and hook members adapted to engage the bridge members connecting the guide members.

5. In a vehicle top, a flexible back member having an aperture, flaps adjacent to the 120 side edges of said aperture, said flaps being folded to form vertical guide grooves, rigid guide members reinforcing said guide grooves adjacent to the top and bottom edges

of the aperture, said guide members being connected in pairs by bridge pieces extending across the aperture, and said guide members being provided with limbs, supporting members for the flexible back member to which the limbs of the guide members are attached, a suitably supported spring actuated roller, and a flexible curtain connected with the roller, said curtain being provided with reinforced side edges engag-

ing the guide grooves and with hook members adapted to engage the bridge members extending across the aperture.

In testimony whereof I affix my signature in presence of two witnesses.

WILLIAM T. MURRAY.
